3 Sheets-Sheet 2

Fig. 2.

A technical drawing of a mechanical device, labeled Fig. 2. The drawing is oriented vertically, with the top pointing upwards. The device consists of a vertical assembly with a central vertical rod. A horizontal plate is positioned above the rod, featuring a central slot. The base of the device has a circular opening. Various components are labeled with numbers: 10, 11, 12, 13, 14, 15, 16, 17, 18, 19, 20, and 21. A hatched area is present on the base plate. The drawing is a line drawing with some shading and hatching.

UNITED STATES PATENT OFFICE.

OMER D. OLIVER, OF GARY, INDIANA.

SWITCH STAND.

Application filed September 9, 1925. Serial No. 55,367.

To all whom it may concern:

Be it known that I, OMER D. OLIVER, a citizen of the United States, residing at 3855 Harrison Street, Gary, in the county of Lake and State of Indiana, have invented new and useful Improvements in Switch Stands, of which the following is a specification.

This invention relates to a switch stand and has for its primary object the construction of a switch stand that will more effectively throw the switch point and lock the same in either of its two positions. An object of the invention is the construction and arrangement of parts wherein the travel of the treadle in one direction will throw the switch point into either of its two positions.

Besides the above my invention is distinguished in the use of catch mechanism for automatically locking the switch points in either of their two positions and automatically releasing the same in the operation of the switch points.

With these and other objects in view, the invention will be better understood from the following description taken in connection with the accompanying drawings.

Fig. 1 is a top plan view of the switch stand.

Fig. 2 is a horizontal sectional view.

Fig. 3 is a side elevational view of the invention with a portion of the housing embodied in the invention removed to illustrate the interior thereof.

Fig. 4 is a vertical sectional view.

Fig. 5 is a detail of the locking means and associated parts, partly in section.

Again referring to the drawings illustrating one of the many constructions of my invention, the numeral 1 designates the usual switch point connected by the bridle bar 2. To the bridle bar is connected the link 3 that connects to a crank 4 carried by the shaft 5. To the upper end of the shaft is connected a signal light 6 while connected to an intermediate portion is a plate 7. This plate 7 is formed with a slot 8 having offset ends 9 and 10. Cooperating with the plate is a rod 11 carrying a pin 12 working in the slot 8. This rod 11 has pivotal connection 13 with a bell crank 14 pivoted to a casing 15 as indicated at 16. The position of the bar 11, slot 10 and pin 12 is such that in the horizontal movement of the rod 11 the plate will be thrown in opposite directions for giving the proper movements to the switch point 1.

My improved mechanism for locking the switch points in their positions and which is automatically operated comprises a dog 17 adapted to interengage with either one of a pair of notches 18 and 19, depending upon the position of the switch point. This dog 17 which is held in its operative position by the spring 20, has a lug 21 arranged to be engaged by catch 22, spring operated and pivotally connected to the bell crank lever.

To complete the invention I provide a treadle 23 having a pin and slot connection 24 with the bell crank lever 14.

From the foregoing description taken in connection with the accompanying drawings it will be seen that when pressure is brought to bear upon the treadle 23 the rod 11 may be thrown forwardly and due to the interengaging action of the pin with either of the offset ends 9 or 10, the plate will be thrown to operate the shaft 5, which in turn throws the switch point. As soon as the switch point has been fully thrown dog 17 moves into the proper notch for locking the mechanism. Upon the return of the treadle in normal position the rod 11 is guided through the slot 8 to the opposite offset end to form another operation when the treadle is depressed and catch 22 is moved into engagement with lug 21 so that when the treadle is depressed the catch will release the dog from further movement and will operate the switch point.

The inner portion of the treadle and associated parts are enclosed in a suitable casing 25 as illustrated. This casing is provided with a slot 26 which receives finger 27 at the upper end of an L-shaped locking bar 28 pivoted at its lower end at 29 to treadle 23 adjacent slot 24. An arm 30 is secured to a stub-shaft 31 rockably mounted in a lug 32 projecting from the inner face of the casing. This arm is connected by pin and slot connections 33 to bar 28 adjacent finger 27 and is so disposed as to direct finger 27 through slot 26 when treadle 23 is released. The finger is of such length as to project through the slot when the treadle is raised and is provided with an opening disposed to receive the shackle of a suitable lock 34. This provides simple and efficient means whereby the treadle can be locked in its normal position and effectually prevents tampering with the switch throwing mechanism.

It is, of course, to be understood that the

various parts may be constructed in various manners and associated in other combinations than illustrated in the drawings, and therefore, I do not desire to be limited in any manner except as set forth in the claims hereunto appended.

Having thus described my invention, what I claim is:

1. A switch stand comprising a housing having a slot formed therein, switch operating means, mechanism for operating said means and locking it in either of its two positions, a member operatively connected to the mechanism and having an end portion movable through the slot, and a locking element detachably fixed to said end portion to prevent movement of the member out of the slot.

2. A switch stand including in combination with a switch point, of an operating plate having a slot formed therein, with offset ends, means operatively connecting the operating plate to the switch point, a foot treadle, and an operating arm operatively connected to the foot treadle and having a portion working in the slot adapted upon depression of the treadle to move into one of the offset ends to operate the operating plate in one direction and adapted upon return of the treadle from depressed position to move in the slot and enter the other offset end to operate the plate in an opposite direction upon return of the treadle to depressed position.

3. A switch stand comprising a switch point operating bar, a shaft having an operative connection with the bar, a plate secured thereto formed with a slot having offset ends, a bell crank lever, a rod pivotally connected to the lever and having a pin moving in said slot, a dog for locking the plate in either of its two positions, a catch on the bell crank for operative connection to the dog for releasing the same and a pivoted treadle having a pin and slot connection with said bell crank.

4. A switch stand including in combination with a switch point, of an operating plate having a slot formed therein with offset ends, means operatively connecting the operating plate to the switch point, a foot treadle, an operating arm operatively con-

nected to the foot treadle and having a portion working in the slot adapted upon depression of the treadle to move into one of the offset ends to operate the operating plate in one direction and adapted upon return of the treadle from the depressed position to move in the slot and enter the other offset end to operate the plate in an opposite direction upon return of the treadle to depressed position, and means operable with the treadle for locking the operating plate against operation.

5. A switch stand including in combination with a switch point, of an operating plate having a slot formed therein with offset ends, means operatively connecting the operating plate to the switch point, a foot treadle, an operating arm operatively connected to the foot treadle and having a portion working in the slot adapted upon depression of the treadle to move into one of the offset ends to operate the operating plate in one direction and adapted upon return of the treadle from depressed position to move in the slot and enter the other offset end to operate the plate in an opposite direction upon return of the treadle to depressed position, and means for locking the treadle against operation.

6. A switch stand including in combination with a switch point, of an operating plate having a slot formed therein with offset ends, means operatively connecting the operating plate to the switch point, a foot treadle, an operating arm operatively connected to the foot treadle and having a portion working in the slot adapted upon depression of the treadle to move into one of the offset ends to operate the operating plate in one direction and adapted upon return of the treadle from depressed position to move in the slot and enter the other offset end to operate the plate in an opposite direction upon return of the treadle to depressed position, means operable by the treadle for locking the operating plate against movement, and means for locking the treadle against movement.

In testimony whereof I affix my signature.

OMER D. OLIVER,
